JULIUS A. MARX, OF ALTOONA, AND WILLIAM W. LOWER, OF TYRONE, PENNSYLVANIA

STORM OR WIND-PROOF SIGN BOARD

Application filed May 29, 1930. Serial No. 457,407.

This invention relates to sign boards or bill boards particularly such as are used in the open country and which are, therefore, subjected greatly to the action of wind.

The main object of our invention is to provide a sign board construction in which the sign is carried upon panels pivoted upon upper and lower elements of the sign board so as to swing open if wind of an undue strength strikes the board, means being provided whereby the panels are normally held closed and in a single vertical plane.

A further object is to provide a construction of this character in which the panels are held against swinging movement under the action of the wind pressure and in which the panels may open in either direction depending upon the direction of the wind.

Other objects will appear in the course of the following description.

Our invention is illustrated in the accompanying drawings, wherein:

Figure 1 is a front elevation of a sign board constructed in accordance with our invention;

Figure 2 is a top plan view with the upper beam removed, the panels and the vertical members being in section;

Figure 3 is a detailed vertical section through a portion of the weight box and the lower frame member;

Figure 4 is a section on the line 4-4 of Figure 1;

Figure 5 is a section on the line 5-5 of Figure 1;

Referring to these drawings, it will be seen that our sign board includes the laterally disposed vertical posts 10. These posts may be made in any suitable manner and of any

suitable material, but preferably the posts are formed as shown in Figure 5 of two three by six uprights 11 and two vertical T-irons 12, the posts being disposed on each side of the webs of the T-irons.

Extending between the posts and above the ground at any suitable distance is the lower transverse member 13 which is preferably formed of two three by six timbers spiked together. Extending longitudinally of the sign and above the element 13 is the element 14

which may be formed in sections or have the full length of the distance between the posts and which is preferably formed of two two by six timbers 15 with a single T-iron 16 having its web extending downward between said timbers, the T-iron resting upon the top thereof as shown in Figure 4. Intermediate supporting members 17 are disposed at spaced intervals between the posts, and intermediate supporting elements 18 are disposed at spaced

intervals beneath the lower element 13, but these supporting elements 18 may well be formed of concrete and the elements 17 may be formed of timber or iron as desired.

It will be seen that the sign space is divided by the members 17 into three sections and disposed in each of these sections are two panels 19. These panels are alike and may be made of any suitable material but preferably they will be formed of a framing designated

20 of strips of wood preferably two by two in cross section supporting an outer and an inner sheet of sheet metal 21. These panels at their upper ends and lower ends are provided with pivot bolts 22 which engage in sockets 23. Preferably the sockets 23 will be formed in conjunction with a metallic plate 24 attachable to the members 13 while the upper and lower ends of the panels will have attached thereto the metal plates 25 to which the bolts 22 are connected.

Preferrably the free ends of the panels will be provided with flexible flaps 26 which will overlap each other when the panels are closed and close any crack or opening which might be otherwise formed between the two panels.

The two panels when closed will be flush with each other. A sign may extend across two of these panels or each panel may carry a separate sign and not only may each panel carry a sign on its front face, but may carry a sign upon its rear face and the panels might be reversed so as to display the signs upon their rear faces to the public or the signs upon their front faces to the public.

The object of this construction, as previously stated is to provide for opening the panels under wind pressure to thereby decrease the wind pressure on the sign itself which sometimes rises to dangerous degrees and which

will be seen that the sign space is divided by the members 17 into three sections and disposed in each of these sections are two panels 19. These panels are alike and may be made of any suitable material but preferably they will be formed of a framing designated

20 of strips of wood preferably two by two in cross section supporting an outer and an inner sheet of sheet metal 21. These panels at their upper ends and lower ends are provided with pivot bolts 22 which engage in sockets 23. Preferably the sockets 23 will be formed in conjunction with a metallic plate 24 attachable to the members 13 while the upper and lower ends of the panels will have attached thereto the metal plates 25 to which the bolts 22 are connected.

Preferrably the free ends of the panels will be provided with flexible flaps 26 which will overlap each other when the panels are closed and close any crack or opening which might be otherwise formed between the two panels.

The two panels when closed will be flush with each other. A sign may extend across two of these panels or each panel may carry a separate sign and not only may each panel carry a sign on its front face, but may carry a sign upon its rear face and the panels might be reversed so as to display the signs upon their rear faces to the public or the signs upon their front faces to the public.

The object of this construction, as previously stated is to provide for opening the panels under wind pressure to thereby decrease the wind pressure on the sign itself which sometimes rises to dangerous degrees and which

requires a very extensive and rigid bracing of signs or bill boards but, of course, it is necessary that the panels shall be returned to their alined position when the wind decreases beyond a predetermined degree and under normal circumstances.

To this end, we have provided weights, one for each pair of panels, and designated 27, these weights each being disposed in a 10 weight box 28 which may be made of wood or any other suitable material, each weight being attached to a pair of chains, cords or other flexible connections 29 which extend up through the top of the weight box, are then 15 angularly deflected and then detachably connected to the free margins of the panels 19. These chains or cords may pass over a pulley or pulleys mounted in the upper end of the weight box or corresponding opening in the member 13, but as shown, we have provided 20 an iron 18a attached to the upper face of the member 13 just above the opening to each weight box and through which iron, chains, cords or cables may pass. Preferably, there 25 will be a flap 30 on each of the panels adjacent its free edge which when the panels are closed will close the groove or guide channel 31 through which the cords or chains 39 pass to thus prevent the entrance of rain or 30 snow to the weight box. It will be seen that we have provided a bill board or sign board construction in which the greater portion of the bill board consists of panels which will automatically open under wind pressure and which will automatically close when the pressure dies down and that we have provided 35 a construction such that the panels may be rotated, if desired, so as to display either or both sides of the panels and further that we have provided a bill board of sign board construction which is very rigid, solid and which does not have to be extraneously braced 40 against wind pressure.

It will be noted that even if the panels 45 are not rotated so as to be reversed from time to time, the sign board may yet display advertisements on its opposite faces. This is not possible with ordinary sign boards because these have to be braced against wind pressure upon one side whereas our sign board does not.

With our sign board, it does not matter 55 whether the wind comes from one direction or the other, the panels are always open, the flexible elements 26 and 30 being sufficiently flexible to permit this, depending upon the direction of the wind.

We do not wish to be limited to the particular construction of the supporting frame for the panels as this might be varied in many ways without departing from the spirit of the invention as defined in the appended claims. Thus: T-iron, angle iron, concrete, 60 iron pipe, or a large number of other differ-

ent structural elements might be used in place of the structural elements illustrated.

We claim:—

1. A sign board including a supporting frame defining a plurality of openings, a pair of panels disposed within each of said openings, the panels being pivotally mounted at their upper and lower ends for swinging movement, and separate and independent means for each pair of panels normally urging each pair of panels to a position where they are flush with each other, but permitting the panels to open under wind pressure. 70 75

2. A sign board including a supporting frame defining a plurality of openings, a pair of panels disposed within each one of said openings, the panels being pivotally mounted at their upper and lower ends for swinging movement, and means, common to each pair of panels normally urging each pair of panels to a position where they are flush with each other, but permitting the panels to open under wind pressure and comprising a weight, a weight box and flexible connections 80 85 extending from the weight, passing out of the weight box and connected to the lower corners of the adjacent free edges of the panels of a pair. 90

3. A sign board comprising lateral posts, longitudinal elements mounted upon said posts and intermediate vertical elements, the posts being formed each of a pair of vertical timbers and a T-iron disposed between said timbers and overlapping the same, the upper longitudinal member comprising two timbers and opposed T-irons having their webs inserted between said timbers, a plurality of pairs of panels disposed between said upper and lower elements and rotatably engaged at their upper and lower ends with said elements, and adapted when closed to be disposed in flush, alined relation to each other, the panels being adapted to carry signs upon opposite faces of the panels, and means normally urging said panels into an alined, flush position, but permitting the panels to open under wind pressure. 95 100 105 110

4. A sign board comprising a supporting frame, a pair of panels pivotally supported within said frame, each for rotation around a vertical axis, said panels normally being disposed in a flush relation with their edges meeting, and means normally urging each pair of panels to a position where they are flush with each other but permitting the panels to open under wind pressure, comprising a vertically movable weight, and a cable attached to the weight and having direct connection with the free edges of the panels, the weight and cable being mounted upon the frame and the frame having a guide member over which the cable passes and disposed in close proximity to the edges of the panel to which the cable is attached. 115 120 125

5. A sign board comprising a supporting

frame, a panel pivotally supported within said frame for rotation around a vertical axis, the panel being normally positioned in a relation parallel to the frame but being swingable in either direction therefrom, and means urging the panel into such parallel relation but permitting the panel to open in either direction under wind pressure including a weight and a cable connected to the weight and connected directly to a free edge of the panel, the weight being supported by the frame and the frame having a guiding means over which the cable passes, the guiding means being disposed immediately adjacent the edge of the panel to which the cable is attached, the guiding means permitting that portion of the cable immediately adjacent the panel to be pulled out in either direction and exert a direct pull on the edge of the panel in all positions of the panel.

In testimony whereof we hereunto affix our signatures.
